his Attorney

UNITED STATES PATENT OFFICE.

PINCUS FARBER, OF SAGINAW, MICHIGAN, ASSIGNOR, BY MESNE ASSIGNMENTS, TO SONORA PHONOGRAPH COMPANY, INC., A CORPORATION OF NEW YORK.

REGISTERING DEVICE FOR TALKING MACHINES.

Application filed July 22, 1918, Serial No. 246,161. Renewed September 12, 1925.

To all whom it may concern:

Be it known that I, PINCUS FARBER, a citizen of the United States, and a resident of the city of Saginaw, county of Saginaw, and State of Michigan, have invented a certain new and useful Registering Device for Talking Machines, of which the following is a specification.

My invention relates to devices by means of which the amount of energy in the power spring of a talking machine motor is indicated at any given time while the spring is under tension, and to indicate the number of records which may be played before the power of the motor is exhausted.

The objects of my invention are to provide a device by means of which the operator may tell at a glance the amount of energy in the power spring, which will be small and inconspicuous, will not easily get out of order, and which will not detract from the appearance of even the most ornate talking machine.

A further object of the invention is the provision of means of the character described, which are extremely simple in construction, thoroughly reliable and efficient in its purpose and operation and inexpensive and economical to manufacture.

With these and other objects in view to be more fully set forth hereinafter, the invention consists in the novel construction, combination of elements, and arrangement of parts which will be exemplified in the construction hereinafter described in the specification and illustrated in the accompanying drawings considered together or separately.

The inventive idea involved is capable of receiving a variety of mechanical expressions, one of which for the purpose of illustrating the invention, is shown in the accompanying drawings.

The invention will be first described in connection with the accompanying drawings illustrating one embodiment of my invention, wherein similar reference characters are used to designate corresponding parts throughout the several views, and then more specifically defined and indicated in the appended claims.

In the drawings—

Fig. 1 is a top plan view of a talking machine motor provided with my invention, the motor board which supports the register and motor being removed.

Fig. 2 is a longitudinal section of the same, the motor being shown in full lines; and

Fig. 3 is a detail side elevation showing the brake for arresting the unwinding of the power spring before the same reaches the condition of ultimate unwinding.

The motor comprises a frame 1 which carries a spring shaft 2 on which one or more spring drums 3, 3^a is or are mounted. Each drum carries a coil spring (not shown). To the inner convolution of the spring in drum 3, is attached a spur gear 4 carried on the shaft 2. The gear 4 meshes with a pinion 5 on a shaft 6 to which a winding crank (not shown) may be applied, and by means of which the springs in both drums may be placed under tension.

The outer convolution of the spring in the drum 3^a is attached to the drum which in turn carries a spur gear 7. The gear 7 meshes with a pinion 8 on a shaft 9 which carries a spur gear 10 in mesh with a pinion 11 on a shaft 12. The shaft 12 carries a bevel gear 13 which meshes with a bevel pinion 14 on the turn-table shaft 15 which projects vertically through the top of the frame 1 and through a motor board 16 which extends across the cabinet (not shown), and encloses the top of the motor.

The turn-table shaft carries a worm wheel 17 which engages and drives a worm 18 on a governor shaft 19. The shaft 19 carries the usual governor 20 having a brake disc 21.

The winding shaft 6 carries a ratchet wheel 22 with which a pawl 23 engages to prevent backward movement of the shaft through the tendency of the power spring to unwind at the winding end. Loosely mounted on the shaft 6 is a lever 24 which is held in frictional engagement with a collar 25 on the shaft 6 by means of a spring washer 26. A pin 27 carried by the pawl 23 projects through a slot 28 in the lever 24.

When the shaft 6 is rotated in the clock-

wise direction to wind the spring, the lever 24 will move with the shaft due to the frictional engagement until its movement is arrested by a stop 29. This movement will raise the pawl from the ratchet teeth. The lever 24 will operate a lever 30 which will apply a brake 31 to the disc 21 which will prevent unwinding of the spring during the winding operation.

10 A pinion 32 on the shaft 6 meshes with a spur gear 33 on a shaft 34, which is threaded at 35. A nut 36 engages the threads 35 and carries a gear wheel 37 in mesh with a long-faced pinion 38 on a shaft 39 on which is mounted a pinion 40 in mesh with the spur gear 7. The nut 36 has a peripheral groove in which rests the jaws 41 of a slide 42 mounted in a guide 43 on top of the frame. A lever 44 is held in engagement with the slide by means of a spring. The opposite end of the lever 44 is attached by means of a pitman 45, to one arm of a bell crank 46, the other arm of which is adapted to be moved into the path of the teeth of the ratchet 22. An arm 47 on the pitman 45 lies in the path of the lever 24.

15 During the winding operation, the pinion 32 will drive the gear 33 and screw 35. The nut 36 will be held against rotation by the 20 brake 31 which prevents unwinding of the power spring, and the nut will therefore be moved along the screw by the rotation of the latter. The nut in its movement longitudinally of the screw will move a slide 48 carried in ways 49. A rack on the slide will 25 swing a lever 50 pivoted to a member 50^a surrounding the turn-table shaft 15 by the engagement of a segmental rack on the lever. The member 50^a has a downwardly projecting portion which acts as a bearing or support for the lever 50, and prevents the lever 50 from bearing against the turn-table shaft, and by reason of such projection, friction 30 and undue wear is eliminated at this point on the turn-table shaft. The opposite end of the lever 50 carries a pin 51 which engages a slot 52 in a lever 53 pivoted at 54 to a plate 55 supported from the motor board. The opposite end of the lever 53 35 carries a toothed segment 56 which engages a pinion 57, which in turn drives a spur gear 58 mounted on a shaft 59 which carries a pointer 59^a co-operating with two scales 60 and 61 on a dial 62. The dial is carried 40 in a frame 63 which is secured to the under side of the motor board, and projects through the same, and is surrounded by a bezel which carries a transparent covering for the pointer.

45 The scales 60 and 61 are differently graduated. The scale 60 is marked for 12 inch records and has less graduations than has the scale 61 which is marked for 10 inch records.

50 When the parts are in the position shown

in Fig. 1, the power springs are run down to the extent permitted by mechanism to be described, and the pointer indicates that there is not enough energy in the springs to run one full record. As the springs are wound and the nut fed along the screw, the leverage system will be swung and the pointer will move in the clock-wise direction and will indicate to what extent the spring has been wound at any moment during the 75 operation, and will indicate the number of records which may be played without re-winding.

Pivoted at one end of the frame 1 is a lever 64, one end of which carries a link 65 having 80 at one end a slot 66, the outer end of which engages a pin in the lever 50. The opposite end of the lever 64 carries a roller 67 which is adapted to engage a cam 68 on a lever 69 pivoted at 70' to one side of the frame. 85 The opposite end of the lever 69 carries a brake shoe 70 adapted to engage the disc 21. With the parts in the position shown, the spring 71 of the lever 50 has pulled the lever 64 to release the cam 68 from the roller 67 90 and the brake 70 is applied.

When the winding operation starts, the pin in the lever 50 will move in the slot 66, and the spring 71^a will cause the roller 67 to engage the cam 68, depress that end of the 95 lever 69, and release the brake 70, but the power spring will still be prevented from unwinding by the brake 31 on the disc 21.

As the winding operation proceeds and the nut 36 moves along the screw, the slide 42 will move with it. When the end of the slide reaches the lever 44, the spring 72 will depress that end of the lever, raise the pitman 45, and throw the free arm of the bell crank 46 into engagement with the ratchet teeth and prevent further winding of the spring. This will occur before the spring 100 has been wound to its ultimate tension.

When the winding crank is released, the 105 tendency of the power spring will be to 110 rotate the shaft 6 backwards. The first movement in this direction will depress the lever 24 and throw the pawl 23 into engagement with the teeth of the ratchet and arrest such movement. At the same time, the 115 end of the lever 24 will engage the arm 47, move the pitman 45 downward, raise the end of the lever 44 against the spring 72 and release the bell crank from the ratchet teeth. The movement of the lever 24 will 120 release the brake 31 and the motor will be free to run.

It will be understood that the motor is provided with the usual hand operated brake to start and stop the operation at the pleasure 125 of the operator.

In accordance with the provisions of the patent statute, I have described the principle of my invention together with the apparatus 130 which I now consider to represent the best

- embodiment thereof, but I desire it understood that my invention is not confined to the particular form of apparatus herein shown and described, the same being merely illustrative, and that the invention can be carried out in other ways without departing from the spirit of my invention, and, therefore, I claim broadly the right to employ all equivalent instrumentalities coming within the scope of the appended claims, and by means of which objects of my invention are attained, and the new results accomplished, as herein set forth, as it is obvious that the particular embodiment herein shown and described is only one of many that can be employed to attain these objects and accomplish these results.
- Having now described my invention, what I claim and desire to secure by Letters Patent is:
1. In a registering device for talking machines, the combination with a spring motor, having a member movable rectilinearly as the spring is wound and unwound, a slide engaging said member, a lever co-operating with the slide, a second lever having a lost motion pin and slot connection with the first lever, a dial having a scale thereon, a pointer co-operating with the dial, and connections between said second lever and pointer for indicating on the scale the number of records capable of being played by the motor without rewinding the spring at any time during the movement of the slide.
  2. The combination with record carrier and means for rotating it, of means for indicating the extent to which the record carrier has been rotated, and including connecting levers operated by the record carrier rotating means and in turn operating the indicator, said levers being pivoted intermediate their ends.
  3. In a registering device for talking machines, the combination with a spring motor for talking machines, having a slide movable as the spring is wound and unwound, a rack on the slide, a lever pivoted to the frame of the motor, a spring for moving the lever in one direction, means cooperating with the winding mechanism for moving the lever in the opposite direction, a segmental rack on the lever engaging the rack on the slide, a pin on the lever, a second lever, said second lever having a slot engaging the pin, a segmental rack on the second lever, said rack engaging a pinion, a gear in mesh with the pinion, a pointer carried by the gear, a relatively small dial with which the pointer co-operates, said dial carrying concentric scales, one of said scales being marked for records of one size, and the other scale being marked for records of another size, whereby as the slide is moved on the winding or unwinding of the spring, the pointer will indicate the number of records of both sizes which may be played from that position of the slide without rewinding the spring.
  4. In a registering device for talking machines, the combination with a spring motor for talking machines, having a slide movable as the spring is wound and unwound, a rack on the slide, a lever pivoted to the frame of the motor, a spring for moving the lever in one direction, means co-operating with the winding mechanism for moving the lever in the opposite direction, a segmental rack on the lever engaging the rack on the slide, a pin on the lever, a second lever, said second lever having a slot engaging the pin, a segmental rack on the second lever, and indicating means operated by said last-named rack.
  5. In a registering device for talking machines, the combination with a spring motor, having means for winding the spring, means for indicating the number of records which may be played without rewinding the spring, and means controlled by the indicating means for preventing winding of the spring to its ultimate tension.
  6. In a registering device for talking machines, the combination with a spring motor, having means for winding the spring, means for preventing winding of the spring to its ultimate tension, means for preventing unwinding of the spring beyond a predetermined point short of complete unwinding, and means for indicating the number of records which may be played without rewinding the spring.
  7. In a registering device for talking machines, the combination with a spring motor, having means for winding the spring, a turn-table shaft, a scale, connections between the motor and the scale whereby the number of records the motor is capable of playing without rewinding is indicated on said scale, said connection comprising a lever pivoted about the turntable shaft, and means for preventing undue wear and elimination of friction on the turn-table shaft caused by the operation of the scale mechanism.
  8. In a registering device for talking machines, the combination with a spring motor, having means for winding the same, a turn-table shaft, means for preventing winding of the spring to its ultimate tension, means for indicating the number of records which may be played without rewinding the spring, comprising a lever pivoted about the turntable shaft and means co-operating with the turn-table shaft for preventing undue wear and eliminating friction thereon.
  9. The combination with a record carrier and means for rotating it, of means for indicating the extent to which the record carrier has been rotated, said means comprising

ing a lever pivoted about the record carrier shaft, and means co-operating with said shaft and lever for preventing undue wear on the shaft.

6. 10. In a registering device for talking machines, the combination with a spring motor having a member movable rectilinearly as the spring is wound and unwound, a slide adapted to be actuated by said member as

the spring is wound, a dial having a scale thereon, a pointer cooperating with the dial, connections between said slide and said pointer, and resilient means for moving said slide in the opposite direction as the spring is unwound.

This specification signed this 15th day of July, 1918.

PINCUS FARB.
